RAY H. COMSTOCK, OF MILWAUKEE, WISCONSIN.

FAUCET ATTACHMENT.

1,369,621.

Specification of Letters Patent. Patented Feb. 22, 1921.

Application filed October 12, 1920. Serial No. 416,452.

To all whom it may concern:

Be it known that I, RAY H. COMSTOCK, a citizen of the United States, residing at Milwaukee, in the county of Milwaukee and State of Wisconsin, have invented new and useful Improvements in Faucet Attachments, of which the following is a specification.

My present invention has reference to a mixing device which is adapted to be connected to the faucet or nozzle of apparatus for delivering carbonated water under pressure to cause the latter to be angularly directed against a body of coca cola or like phosphate syrup which has been placed in a glass that is arranged to receive the mixing device therein, and whereby such syrup will be contacted by the angularly directed sprays from the mixing device so as to thoroughly mix the syrup with the carbonated water without the necessity of the employment of a spoon, or like manually operated mixing device for accomplishing this purpose.

A further object is the production of a mixing device for this purpose which is of a simple construction, may be cheaply manufactured, readily attached to the faucet of a soda water fountain, and which will effectively mix a phosphate syrup with the carbonated water that is drawn from the fountain.

The foregoing, and other objects which will appear as the nature of the invention is better understood, may be accomplished by a simple construction, and arrangement of parts, such as is disclosed by the drawings which accompany and which form part of this application.

In the drawings:—

Figure 1 is a view illustrating the improvement attached to the faucet of an ordinary soda water fountain.

Fig. 2 is an approximately central vertical longitudinal sectional view through the improvement.

Fig. 3 is a bottom plan view of the improvement.

Fig. 4 is a sectional view, on an enlarged scale, and approximately on the line 4—4 of Fig. 1.

Referring now to the drawings in detail, the numeral 1 designates a faucet of a soda fountain. The faucet has its outlet end provided with the usual outstanding bead 2. My improvement is broadly indicated by the

numeral 3, and has a body portion in the nature of a tube 4. The improvement 3 is constructed of some suitable material which is not affected by the acids in the carbonated water, and the tube 4 has its upper end formed with an enlarged socket portion 5. On the shoulder 6 which provides the lower wall between the socket and the tube there rests a gasket 7 preferably in the nature of a cork ring, and the socket 5 has any desired number of spaced threaded openings therethrough, the spaced openings being in a line with each other. Through these openings pass the threaded shanks of small bolts 8. The bolts contact with the faucet and with the upper edge of the bead 2, compressing the mouth of the faucet against the gasket. Of course, other means may be provided for attaching the improvement to the faucet.

In the process of construction, the lower end of the tube 4 is flared outwardly, or is funnel-shaped and is cut longitudinally from the outer end thereof. The material bounded by the cuts or slots have what I will term the inner corners thereof rounded inwardly upon themselves, as at 9 to provide channels 10 which are directed at an outward angle with respect to the tube 4. The outer faces of the portions bounded by the slots, indicated for distinction by the numeral 11 are bent upon themselves at an angle which is directed from adjacent to the outer lower corners of said members, or rather toward the center of the said members at their connection with the tube 4. Thus the outer faces of the said portions are substantially V-shaped, as indicated by the numeral 12. The portions above described are in the nature of directing members, and will hereinafter be referred to as such.

The directors are so shaped as to allow either a fine or large stream of carbonated water passing through the faucet, and when a glass having a quantity of syrup which is to be mixed with the carbonated water, is positioned to receive the improvement therein, the improvement is allowed to rest on the bottom of the glass where it will be covered by the syrup. The carbonated water flowing through the improvement and contacting with the directors will be distributed at three opposed angles into the syrup and will also contact with the sides of the glass, thus causing a whirling motion to be imparted to the carbonated water and the syrup. The improvement is held at the bot-

tom of the glass until the glass is three-fourths full, when the glass is gradually lowered in the filling thereof.

Having thus described the invention, what I claim, is:—

A mixing device adapted to be connected to a liquid dispensing apparatus, comprising a tube, directing members at the lower end of the tube disposed at opposite outward

angles with respect to each other and having 10 their inner edges, adjacent their outer ends, rounded upon themselves to provide tongues and their outer faces arranged at an upward angle from adjacent their outer corners to approximately the central portions thereof 15 at their connection with the tube.

In testimony whereof I affix my signature.
RAY H. COMSTOCK.
